UNITED STATES PATENT OFFICE.

PHILIP C. P. BOOTY, OF CHICAGO, ILLINOIS, ASSIGNOR, BY MESNE ASSIGNMENTS, TO LESLIE W. FRICKE, OF OAK PARK, ILLINOIS.

DESIGN FOR A MANICURIST'S POLISHING IMPLEMENT.

Application filed December 20, 1923. Serial No. 8,100. Term of patent 14 years.

To all whom it may concern:

Be it known that I, PHILIP C. P. Booty, a subject of the King of Great Britain, residing at Chicago, in the county of Cook and State of Illinois, have invented a new, original, and ornamental Design for a Manicurist's Polishing Implement, of which the following is a specification, reference being had to the accompanying drawing, forming part thereof.

In the drawings—

Fig. 1 is a perspective view and Fig. 2 is a side elevational view of a manicurist's polishing implement, embodying my new design.

I claim:

The ornamental design for a manicurist's polishing implement, as shown.

PHILIP C. P. BOOTY.
